(57) **CLAIM**

The ornamental design for an electrode cage for a plasma blasting probe, as shown and described.

DESCRIPTION

FIG. 1 is a perspective view of an electrode cage for a plasma blasting probe showing our new design.

FIG. 2 is a side view thereof;

FIG. 3 is a bottom view thereof; and,

FIG. 4 is a top view thereof.

The broken lines shown in the drawings represent portions of the electrode cage for plasma blasting probe that form no part of the claimed design.
